UNITED STATES PATENT OFFICE.

HAROLD GRIFFITHS, OF SHREWSBURY, MASSACHUSETTS.

JACQUARD HARNESS.

Application filed April 13, 1927. Serial No. 183,479.

The invention relates to jacquard harness, particularly to harness used in that type of jacquard machine which employs lifting boards. This type of jacquard is extensively used as the shedding mechanism for carpet looms, and to such my invention is particularly applicable, although not restricted to use in connection with carpet looms.

The chief type of harness heretofore used with lifting board jacquards has been ordinary braided cordage, said cordage being knotted just above the several lifting boards and above the top or suspension board. Upon this cordage, during the operation of the loom, there is a continual friction and a continual strain as the individual cords are lifted to form the shed. This has resulted in breakage of the individual cords, and while any given cord will normally last for a great length of time, breakage is not infrequent in any given jacquard because over a thousand cords are used in each machine.

Every time a cord breaks, the loom has to be stopped until it is fixed. Moreover, the replacing of an old cord with a new one necessarily means that the lengths of the cords will ultimately vary, since the stretch on all the cords can no longer be said to be even theoretically uniform. If the cords are not all of the same effective length, an uneven shed will be produced. Also, cords of unequal length and stretch are more apt to get tangled and sometimes do not enter the slot in the lifting board effectively so as to be lifted when the pattern calls for such.

Another difficulty encountered in jacquards of this class with the cordage heretofore in use, is the shrinking which occurs on a damp or humid day. On such a day all of the cordage shrinks, sometimes to such a great extent that the shuttle cannot pass through the shed. When this happened, the loom had to be shut down, with a consequent serious loss of production.

To remedy all this, the invention provides rigid wires passing through the lifting board that determines the color pattern, commonly known as the trap board, and extending into the top or suspension board. When, by the action of the said trap board, the selected harness elements are raised, the tops of said elements rise above the top or suspension board. Thus there is no flexing of any of the harness elements, and consequently they will last much longer and will always be properly aligned with the lifting slots when moved

into position for lifting by the cross wires. And, of course, the wires are unaffected by humidity.

The invention is herein illustrated in two modifications, and further modifications may be made. The top board in some cases may be used as the lifting board that determines the shed. But in all modifications, the rigid or wire harness extends between and through the top board, whether it is a suspension board or a lifting board, and the immediately subjacent board, which is a slotted board and lifts the harness elements selectively, as determined by the jacquard cards and the cross wires. All of which will more fully appear in the following detailed description taken in connection with the accompanying drawings, in which—

Fig. 1 is a vertical sectional view through a jacquard machine showing the invention applied thereto in the form of flat harness wires, with the topmost board being used as a lifting board.

Fig. 2 is a side elevation of the board moving mechanism of a jacquard machine, showing how the top board is actuated when it is used as a lifting board.

Fig. 3 is an enlarged fragmentary plan view of the top board.

Fig. 4 is an enlarged fragmentary plan view of the slotted lifting, or trap board.

Fig. 5 is a still further enlarged and detail view of a device used for removably retaining the harness wires in place.

Fig. 6 is an enlarged view of a single flat harness wire as used in the invention, showing that part of it which extends through the top board and the trap board.

Fig. 7 is a fragmentary vertical sectional view, showing a modified form of harness.

Like reference characters refer to like parts throughout the drawings.

Referring first to Fig. 1, which is simply a fragmentary showing of so much of a jacquard as is necessary to the understanding of my invention, the top board which, in this embodiment of the invention, is given a rising and falling motion as will hereinafter be described, is designated by the reference numeral 1. Said board 1 provides a plurality of holes 2 (best shown in Fig. 3) through which extend the harness wires 4 of the invention. The wires 4 extend downwardly through holes provided in a trap board 5. Below the trap board 5 are the usual cross wires or needles 6 that are actuated by the

jacquard cards to determine the pattern. Said needles 6 are supported by plates 7 and 8 through which they pass and they provide loops 9 surrounding the wires 4. It is unnecessary to describe the particular arrangement of the wires and loops, as such forms no part of the present invention, and indeed the invention makes no change over the prior practice in this respect.

Below the needles or cross wires 6 is a guide board 10, providing slots for the passage of the wires 4. In this embodiment of the invention, the wires 4 are constructed, as shown in Fig. 6, out of flat wire, having two 90° twists at 11 and 12, respectively, leaving a portion 13 which extends at right angles to the plane of the rest of the wire. The portion 13 constitutes the means by which the wires are lifted by the trap board 5, as will be hereinafter described. The wires 4 also provide caps 14 to prevent them from falling through the top board, and they extend downwardly far below the jacquard proper into the loom, being spaced therein by another guide board 15. The wires 4, in fact, terminate just above the heddle eyes 16 (sometimes termed mails), which control the individual ends of the color warp, although it is in the contemplation of the invention that the said mails may be dispensed with and slots through the flat wire substituted therefor. At all events, they extend practically the whole distance from the top of the jacquard right down to the warp in the loom, being held firmly in vertical position by the usual individual weights 17, commonly known as lingoos.

The so-called card cylinder is shown at 18 in Fig. 1, and the levelling-up board is shown at 19. The former carries the pattern cards, not shown, which, when the card cylinder is moved to the left, selectively moves some of the needles 6, thus moving the corresponding wires 4 slightly to the left. When this happens, the wires 4 that are moved pass from large holes 20 (see Fig. 4) in the trap board to slots 21 therein, except that in the case of the two left hand rows of wires the reverse is the case. At all events, when the trap board 5 rises, which it does imminently after this selective moving of the wires 4, those wires that are in the narrow slots 21 are raised, by reason of the fact that the portions 13 will not fit the slots.

In Fig. 3 is shown a fragmentary plan view of the top board 1. As aforesaid, this board provides a number of holes 2 equal to the number of wires 4 which pass through it. Across each row of holes is a member 22 providing slots 23. These slots serve to align the wires 4. A member 22 is more clearly illustrated in Fig. 5, and provides screw holes 24, 24 for detachably securing it to the board 1. The reason for providing these members 22 rather than making slots of the required size and shape in the board 1 is that

the wires must be inserted into the jacquard from above and the portion 13 could not be forced down through such slots in the board 1. Consequently, when initially assembling the wires 4 in the jacquard, or in case one of the wires 4 should for any reason have to be replaced, any one or all of the members 22 can be removed until the portion or portions 13 have been lowered below the board 1, whereupon that particular member 22, or all of them, can be reinserted in place and screwed down.

Besides selectively raising certain ends of the figuring warp (in the case of carpets, the pile) to produce the pattern, a jacquard of this type must periodically (usually at alternate picks of the loom) raise all the figuring warp in order that the weft or filling may bind the whole together. This is accomplished by raising all of the harness elements 4. Heretofore, this has been accomplished by a lifting board, which was located below the guide board 10. In the particular modification of the invention shown in Figs. 1 to 6, however, this function is performed by the top board, and in order to give this board the necessary periodic motion, the following adaptation of the usual mechanism is provided. Referring to Fig. 2, 25 indicates the low or cam shaft of the loom which revolves once in every two picks of the loom. An eccentric cam 26 is secured to this shaft on each side of the loom, and each of said cams engages with a roller 27 carried by a lever 28 which is pivoted at 29 to the loom frame. Lifting connectors 30 connect the free ends of the levers 28 to the board 1, which is shown in Fig. 2. Guides 31 and 32 projecting from the jacquard frame 33 compel the board 1 to move in a rectilinear path.

As the shaft 25 revolves at half the speed of the crank shaft (not shown), the board 1 will be lifted on alternate picks of the loom, the cams 26 being of the single rise and fall variety. The connectors 30 provide arms 34 which raise and lower a harness frame 35 that carries what is known as the stuffer warp. In Fig. 2 are shown the principal elements of the mechanism to operate the trap board, deriving its motion from a cam 36 on the cam shaft 25, but as this mechanism and the associated mechanism for actuating the card cylinder 18 and the levelling up board 19 are unchanged by my invention, they need not be further described herein.

Reverting now to the objects of the invention set forth at the beginning of this specification, it is obvious that there can be no shrinkage of the wire harness elements 4. There is no flexing of the wires, since when the trap board 5 lifts, raising certain of the harness elements 4, said elements rise above the top of the board 1. Neither is there any flexing when all the warp ends are raised together since, according to this embodiment of the invention, the wires 4 are held firmly in vertical position by the weights 17.

the invention, this is performed by a board at the top of the jacquard instead of by a board located underneath the cross wires 6 as formerly. But the invention, in this aspect, 5 is not limited to the use of flat wire, nor to the use of the twist 13 to catch in the slots of the board, nor to any particular form of projection 14 for preventing the wires from falling through the top board.

10 Turning now to Fig. 7, a modification of the invention is indicated in this fragmentary view. The top board, which in this embodiment is a stationary suspension board, is indicated at 37. The trap board is indicated at 38, 15 the guide board just below the needles at 39, and the board which is raised at periodic intervals to raise all the warp at 40. The motions and construction of the parts of the jacquard are, in fact, unchanged from the usual 20 practice, in jacquards for carpet looms of this type in this embodiment, the harness elements alone being different,—for this reason the invention can be applied in this form to existing jacquard machines without any change in 25 their construction.

The harness elements comprise a stiff wire 41, which may be round or of other cross sectional shape, said stiff wire extending from the top of the jacquard well below the guide 30 board 39; extending through the board 40 to the mails, the harness elements comprise twisted flexible strand wire 42. The bottom part of each individual length of wire 41 is perfectly straight before it is placed in the 35 jacquard and it may thus easily be inserted therein from the top, passing through holes in the trap board and through the needle eyes and the guide board; when a wire is so inserted, its lower end is hooked over as shown at 40 43, and thereupon the proper flexible wire 42 may be attached by simply placing a loop 44 formed thereon over the said hook.

Some sort of a knot or projection 45, which 45 may be soldered on, is provided on the wire portion 42, so that the board 40 may lift the figuring warp. A twist or a similar projection 46 is provided in the stiff wire 41 to enable the trap board to selectively lift the desired warp ends and similar means is provided at 47 to prevent the wires from falling through the top suspension board 37.

Although, according to this modification of the invention, the wires 42 do flex, the upper wires 41 do not; instead, when lifted by the 5 trap board, the tops of said wires project through the top suspension board 37 as in the first embodiment of the invention. As it is in the jacquard proper that the principal wear and tear on the harness cords has occurred, 10 owing to the fact that the flexure here must occur in a shorter lineal distance and hence is more pronounced, and owing to the fact that the movement of the trap board is a sharper movement (see the shape of the cam 36 as 15 compared with the shape of the cam 26), this

modification of the invention shown in Fig. 7 possesses the principal advantage of the embodiment first described, and in addition, can be applied to jacquard machines now in operation without any change. 70

Both embodiments of the invention are immune to the effects of adverse atmospheric conditions, and insomuch as this would be so even if, in the second embodiment, the part 42 of the harness elements were made of cord 75 (the lengths of the parts 42 being so short), I intend to include this obvious slight change in the invention within the scope of the appended claims. 80

I claim,

1. In a jacquard machine, a top board, a selectively lifting board, and a set of stiff harness elements extending through the selectively lifting board and the top board, means to hold said elements from falling through the top board, and means for lifting them by the rise of the selectively lifting board, whereby said action takes place without flexure of the harness elements. 85

2. In a jacquard machine, a top board, a selectively lifting board, a set of stiff harness elements providing means to hold them from falling through the top board and means for lifting them by the rise of the selectively lifting board, and detachable guiding members 90 to guide said harness elements in said top board, yet allowing them to be readily inserted therein, whereby movement of the harness elements takes place without flexure. 95

3. In a jacquard machine, a top board, a selectively lifting board, and a set of flat metal harness elements extending through the selectively lifting board and the top board, means to hold said elements from falling through the top board, and means for lifting them by the rise of the selectively lifting board, whereby 100 said action takes place without flexure of the harness elements. 105

4. In a jacquard machine, a top board, a selectively lifting board, a set of flat metal 110 harness elements providing means to hold them from falling through the top board and means for lifting them by the rise of the selectively lifting board, and detachable guiding members to guide said harness elements in 115 said top board, yet allowing them to be readily inserted therein, whereby movement of the harness elements takes place without flexure.

5. In a jacquard machine, a top board, means to periodically move said top board, a selectively lifting board, and a set of stiff harness elements providing means to hold them from falling through the top board and means for lifting them by the rise of the selectively lifting board, whereby said action takes place 120 without flexure of the harness elements. 125

6. In a jacquard machine, a top board, means to periodically move said top board, a selectively moving lifting board, a set of stiff harness elements providing means to hold 130

them from falling through the top board and means for lifting them by the rise of the selectively lifting board, and detachable guiding members to guide said harness elements in said top board, yet allowing them to be readily inserted therein, whereby movement of the harness elements takes place without flexure. 7. In a jacquard machine, a top board, means to periodically move said top board, a selectively lifting board, and a set of flat metal harness elements providing means to hold them from falling through the top board and means for lifting them by the rise of the selectively lifting board, whereby said action

takes place without flexure of the harness elements. 15

8. In a jacquard machine, a top board, means to periodically move said top board, a selectively lifting board, a set of flat metal harness elements providing means to hold them from falling through the top board and means for lifting them by the rise of the selectively lifting board, and detachable guiding members to guide said harness elements in said top board, yet allowing them to be readily inserted therein, whereby movement of the harness elements takes place without flexure. 20 25

HAROLD GRIFFITHS.
